ATTORNEYS.

UNITED STATES PATENT OFFICE.

EMMIT G. LATTA, OF SYRACUSE, NEW YORK.

TYPEWRITING-MACHINE.

1,382,791.

Specification of Letters Patent. Patented June 28, 1921.

Application filed October 30, 1918. Serial No. 260,247.

To all whom it may concern:

Be it known that I, EMMIT G. LATTA, a citizen of the United States, residing at Syracuse, in the county of Onondaga and 5 State of New York, have invented a new and useful Improvement in Typewriting-Machines, of which the following is a specification.

This invention relates more particularly 10 to improvements in portable front strike, or visible writing, typewriting machines of the character disclosed in my copending application, Serial No. 123,160, filed Sept. 30, 1916, now Patent 1,331,441, Feby. 17, 1920. Said application discloses a front strike 15 typewriter which is equipped with a full size keyboard comprising a complete set of finger keys arranged as usual in banks, a full set of pivoted type-bars actuated there- 20 by, a rotary paper platen on a transversely traveling carriage, and other coöperating parts such as are employed in standard makes of typewriters, but in which all of the operative parts of the machine are mounted on 25 a single rigid frame and arranged to adapt the machine to be lowered from its operative position so as to occupy a very much smaller space for convenience in transportation.

The objects of the invention are to provide 30 a portable typewriter of this kind with a supporting base which will hold the machine securely and rigidly in operative position under the most severe conditions of use, and which will permit the machine to be re- 35 duced in dimensions and restored to operative condition with greater ease and speed than prior constructions; also to make the action of the parts in reducing and restoring the machine practically automatic, the ma- 40 chine being moved and held in one direction by a spring, and in the other direction by gravity; also to so design and arrange the machine parts that while the type-bar segment is located so as to be a material 45 distance above the top of the desk or machine support when the machine is in use, it can be lowered to the level of the supporting surface for portability without interference of such parts; also to provide a base 50 that can be suitably secured to the support, as by screws passing through the desk top into the base, and will yet permit the machine to be lowered without removal from the support when it is not desired to trans- 55 port the machine; also to provide a base that

is not prone to creep on the supporting surface under the repeated impulses of returning the carriage for new lines.

In the accompanying drawings:

Figure 1 is a fragmentary longitudinal 60 sectional elevation of a typewriting machine embodying the invention.

Fig. 2 is a side elevation showing the machine in the recumbent position to which it is moved for reducing its dimensions. 65

Fig. 3 is a fragmentary side elevation of a modification of the connection between the main frame and the supporting base.

Fig. 4 is a sectional plan view of the machine on line 4—4, Fig. 2. 70

The typewriter comprises as usual, finger keys A arranged in banks or rows, preferably four rows, at the lower front portion of the machine, a paper platen B journaled to rotate on a transversely movable carriage

75 B' at the rear portion of the machine and printing instrumentalities arranged between the finger keys and carriage and preferably comprising a series of type-bars C pivoted in the usual arcuate order on a curved seg- 80

ment C' and the connections whereby the type-bars are actuated by the operation of the finger keys. Other parts of the ma- 85

chine, such for instance as the paper feed rolls D, one of the ribbon spools E, the paper 85

table F, the carriage escapement wheel G, feed pinion g and rack bar H on the carriage meshing with the pinion for controlling the letter space movements of the carriage, the driving spring drum I for the carriage, the 90

space bar K, the universal bar k, the back stop or basket L for the type bars, line space lever M, the carriage release lever N and the feed roll release lever O are, however, in- 95

icated in the drawings to show their posi- 100

tions and relative arrangement in the ma- chine and illustrate the convertibility of the machine. All of these parts are mounted in the relation to each other shown in the 105

drawings and above briefly stated, on a sin- gle, rigid main frame which is movably mounted on a supporting base, as herein- 110

after described, so that the frame is adapted to be supported stationarily in an operative inclined position, as shown in Fig. 1 with the rear portion of the frame and platen car- 110

porting base, as shown in Fig. 2 whereby the machine is materially reduced in dimensions so that it can be placed in a carrying case of the small inside vertical dimensions indicated by the broken lines $a-b-c-d$ shown in Figs. 1 and 2.

The main frame preferably comprises vertical side plates 10 and 11 of the shape shown in Fig. 2 which are rigidly connected by front and rear bars 13 and 14 and an intermediate bar 15 which supports a guide or track 16 for the platen carriage. The side plates are also shown as connected by cross bars 17 and 18 which support the key action. The finger key and type-bar actions are preferably substantially the same as shown in my said application and the shiftable type-bar segment is similarly supported by arms 19 and 20 rigidly connected to rock shafts 21 and 22 having their ends suitably journaled in the side plates of the main frame. The segment is shifted for upper case work by a shift lever 23 provided with a key 24 at its front end and rigidly secured at its rear end 25 to the rock shaft 21.

Some parts of the machine, such as the ribbon and its vibrator and driving mechanism, the connection between the universal bar and carriage escapement wheel, and the retracting springs for the movable parts are omitted from the drawings as they are not necessary to an understanding of the invention.

All of the parts mentioned are designed and arranged so that they are located substantially within the space bounded by the planes represented by the lines $a-b-c-d$. In the operative position of the machine the plane $a-b$ inclines upwardly and rearwardly from the foremost bank of finger keys over the platen B substantially tangential thereto, and the plane $c-d$ inclines upwardly parallel with the plane $a-b$ from a point well in front of the center of gravity 45 of the machine under and near the pivot ends of the lowermost type-bars and terminates at its rear end at a point about half as high as the rear end of the plane $a-b$. The frame side plates 10 and 11 preferably terminate at their lower edges substantially in the plane $c-d$. The lowest part of the type-bar segment in its normal position extends slightly below the plane $c-d$, but the segment is adapted, when the machine is lowered, to move upwardly to or beyond said plane so that in the reduced condition of the machine all of the parts are located between said planes $a-b$ and $c-d$.

The machine as thus far described is substantially like that disclosed in my said application.

25 represents a base or plate preferably consisting of a casting extending from side to side of the machine and having seats for four rubber feet or cushions 26. 27 indi-

cates holes in the base for the reception of screws for securing the base on a desk or other support. The main frame is hinged to the front portion of the base 25, preferably by screws 28 passing through the side plates 10 and 11 into upstanding ears 29 on the ends of the base.

30 represents a pair of folding legs for supporting the rear end of the main frame. Preferably these legs are rigidly secured to the opposite ends of a shaft 31 which is adapted to rock in bearing lugs on ears 31^a at the rear end of the base. The legs are provided at their free ends with outwardly projecting studs 32 which slidably connect the legs to the side plates of the main frame. As shown in Figs. 1, 2 and 4, the studs pass through and are adapted to slide in longitudinal slots 33 in the lower central parts of the side plates while in the modified construction shown in Fig. 3, the studs slide in open bottomed recesses 33^a in the lower edges of the side plates provided at their rear ends with hooks or projections 33^b which extend under the studs when the legs are in upright

supporting position to prevent the accidental lifting of the frame off of the legs. The studs are provided at their outer ends with heads or enlargements 34 which engage the outer faces of the side plates and prevent the inward deflection of the free ends of the legs or the lateral disengagement of the studs from the side plates in the event of an unusual strain or thrust on the machine. The legs are acted upon by a suitable spring or

springs, such as springs 35 coiled about the rock shaft 31 with their opposite ends respectively attached to the shaft and bearing against the base plate 25. If the rear end of the machine is raised from the recumbent position shown in Fig. 2, these springs will rock the shaft and swing the legs upwardly until arrested in the upright supporting position shown in Fig. 1 by the engagement of the studs 32 with the rear ends of the slots or recesses in the side plates, and will yieldingly retain the legs in this position. The machine is then ready for use without further attention.

When it is desired to lower the machine to reduce its dimensions, the forefinger of one hand is placed against the curved rear edge 36 of one of the legs and this leg and the other one which is connected therewith are thus moved forwardly until their studs 32 pass the dead center position when the weight of the machine will cause the parts to assume the recumbent position shown in Fig. 2 and to retain that position with the lower edge parts 37 of the side plates resting on the supporting surface without further attention. When thus lowering the machine the segment will be shifted to upper case position by engagement with the supporting surface. The curved rear edges 36 of the legs are to relieve the appear-

ance of straight lines and prevent the operator from pinching his finger when lowering the machine.

When in position for use, the whole machine is supported by the four rubber feet the same as in machines having such feet fixed directly to the main frame. By the described construction the action of reducing the machine and restoring it to operative condition is practically automatic. When 10 raising the machine the springs 35 cause the arms to swing back past the dead center and lock in supporting position, and when lowering the machine its weight acts automatically to secure it in the lowered position. By mounting all operative parts of the typewriter on the single rigid main frame they can be adjusted with the utmost nicety and will retain their adjustment the same as in 20 standard non-portable machines. The construction described provides a front strike type-bar machine with a full set of finger keys, type-bars and other parts such as employed in standard makes of front strike typewriters and capable of doing the same 25 class of work, and in which all operative parts of the machine are mounted on a single rigid frame in such a way as to enable the reduction of the machine to the small dimensions described.

I claim as my invention:

1. In a typewriting machine, the combination of a main frame normally extending from front to rear at an upward inclination 35 and having a keyboard at its front, a series of type-bars in rear of the keyboard, and a platen carriage in rear of and above the type-bars all permanently arranged on the main frame, a frame base pivotally connected at its front to the lower part of the main frame, and means mounted on the base and movable to hold the main frame in its normal position or to permit it to assume a horizontal position on the base, said means 40 being connected to both the main frame and the base and acting to limit the movement of the base away from the main frame.

2. In a typewriting machine, the combination of a frame base, a main frame adapted 50 to rest horizontally on the base and pivotally connected to the front thereof, a keyboard and a platen carriage mounted respectively on the front and rear portions of the main frame, a series of front strike type-bars 55 mounted on the main frame between the keyboard and carriage, and a pivotal support for holding the rear of the main frame in an elevated operative position, or permitting it to assume a horizontal position on the base 60 without disturbing the operative relation of the keyboard, type-bars and carriage, said support being connected to both the main frame and the base and acting to limit the movement of the base away from the main 65 frame.

3. In a typewriting machine, the combination of a main frame having a keyboard, front strike type-bars and a platen carriage arranged in operative relation thereon, a frame base having its front pivotally connected to the main frame, and means adjustable to hold the main frame in operative position on the base and to positively lower the main frame, and at all times connecting the base to the main frame. 70

4. In a typewriting machine, the combination of a main frame having a keyboard, front strike type-bars, and a platen carriage arranged in operative relation thereon, a frame base having its front pivotally connected to the main frame, and pivotally mounted legs connecting the rear of the base to the main frame at all times, and movable to permit the rear of the main frame to be raised above the base and support it in such 80 position.

5. In a typewriting machine, the combination of a main frame having a platen carriage, a keyboard and front strike type-bars arranged in operative relation thereon, a frame base having its front pivotally connected to the main frame, and a rock shaft mounted on one of said frame parts and having legs rigid therewith connecting the rear of the base to the main frame. 90

6. In a typewriting machine, the combination with a two-part frame, comprising a main frame having a platen carriage, a keyboard and front strike type-bars mounted in operative relation thereon, and a frame base 100 having its front pivotally connected to the main frame, of a rock shaft mounted on one of said frame parts, said rock shaft having rigid legs extending therefrom, and movable connections between the free ends of said 105 rigid legs and the other frame part.

7. In a typewriting machine, the combination of a main frame having a platen carriage, a keyboard, and front strike type-bars mounted in operative relation thereon, a frame base 110 having its front pivotally connected to the lower part of the main frame, a rock shaft mounted on the base and having rigid legs with sliding bearings on the main frame, and stops for said legs. 115

8. In a typewriting machine, the combination with a two-part frame comprising a main frame having a platen carriage, a keyboard, and front strike type-bars mounted in operative relation thereon, and a frame base having its front part pivotally connected to the main frame, of a rock shaft mounted on one of said frame parts, said rock shaft having rigid legs extending therefrom, and movable and interlocking bearings 120 between said rigid legs and the other frame part. 125

9. In a typewriting machine, the combination with a two-part frame comprising a main frame having a keyboard, a platen car- 130

riage, and front strike type-bars mounted in operative relation thereon, and a frame base having its front pivotally connected to the main frame, of a rock shaft mounted on 5 one of said frame parts, said rock shaft having rigid legs extending therefrom, movable connections between said rigid legs and the other frame part, and a spring for rocking said shaft and legs in the direction to 10 hold the main frame in operative position.

10. In a typewriting machine, the combination with a two-part frame comprising a main frame having a keyboard, a platen carriage and front strike type-bars mounted in 15 operative relation thereon, and a frame base pivotally connected at its front portion to said main frame, of a support for the rear portion of the main frame pivoted on one of said frame parts, movable connections be- 20 tween said support and the other frame part, and a spring acting to move said support in the direction to hold the main frame in operative position.

11. In a typewriting machine, the combination of a main frame, a frame base to 25 which said main frame is hinged to permit the rear portion of the main frame to swing up and down, a support for the rear portion of the main frame which connects the main 30 frame and base at all times and is adjustable to stationarily support the main frame and to permit the lowering of its rear end, and a keyboard, platen carriage and type-bars all mounted in operative relation on said 35 main frame.

12. In a typewriting machine, the combination with a two-part frame comprising a main frame and a frame base to which said main frame is hinged to permit the rear portion 40 of the main frame to swing up and down, of a support for the rear portion of the main frame pivoted on one of said frame parts, adjustable connections between said support and the other frame part for stationarily supporting the main frame and 45 permitting the lowering of its rear portion, and a keyboard, platen carriage and type-bars all mounted in operative relation on said main frame.

50 13. In a typewriting machine, the combination with a two-part frame comprising a main frame and a frame base to which said main frame is hinged to permit the rear portion of the main frame to swing up and down, of a support for the rear portion of the main frame pivoted on one of said frame parts, slidable connections between said support and the other frame part for stationarily supporting the main frame and permitting the lowering of its rear portion, 55 and a key-board platen carriage and type- 60

bars all mounted in operative relation on said main frame.

14. In a typewriting machine, the combination of a main frame, a frame base to 65 which said main frame is hinged to permit the rear portion of the main frame to swing up and down, a support for the rear portion of the main frame pivoted on said base and slidably connected to said main frame for 70 stationarily supporting the main frame and permitting the lowering of its rear portion, and a keyboard, platen carriage and type-bars all mounted in operative relation on 75 said main frame

15. In a typewriting machine the combination of a main frame having a platen carriage, a keyboard and front strike type-bars all mounted in operative relation on said frame, a frame base having its front end 80 pivotally connected to the main frame, and a rock shaft mounted on said base and having legs rigid therewith and connected to said main frame to move from one to the other side of the center of gravity of 85 the main frame, whereby the weight of the main frame and parts thereon tends to hold said legs in both an operative and an inoperative position.

16. In a typewriting machine, the combination of a main frame supporting the operative parts of the machine, a frame base pivotally connected to the front part of the main frame, a pivotal support connecting the rear portions of the main frame and 95 base and arranged to be held in an inoperative position by the weight of the machine, and a spring which tends to move the support to a position in which it supports the rear end of the main frame elevated. 100

17. In a typewriting machine, the combination of a main frame having a platen carriage, a key-board and front strike type-bars mounted in operative relation thereon, a frame base having its front pivotally connected to the main frame, and a movable rear connection between said main frame and said base to permit the rear of the main frame to be raised above the base or lowered to rest on the base, said movable rear connection being mounted to swing past a dead center position and being held at one side of such position by the weight of the machine, and a spring for resiliently holding the connection on the other side of said dead center 110 position. 115
